UNITED STATES PATENT OFFICE

2,499,282

ROCK BIT

William A. Roberts, Lakewood, Colo.

Application July 11, 1946, Serial No. 682,889

1 Claim. (Cl. 255—64)

1

This invention relates to an improved rock drill bit which is especially adapted to cut and break small rock that falls down the hole behind the bit during the drilling operation.

An object of the invention is to provide a drill bit having cutting edges on the top surface thereof of which will cut rocks that fall on the top of the bit and jam the bit in the hole, sometimes making it impossible to loose the bit from the hole.

The present type of bits that are being used do not provide means for cutting the falling rocks and it requires extra labor, material and expense to remove such bits from the hole when jammed. However, the present bit, which is provided with cutting edges on the top surfaces of the cutters, will cut this fallen rock and aid in removing the bit from the hole.

With the above and other objects and advantages in view, the invention consists of the novel details of construction, arrangement and combination of parts more fully hereinafter described, claimed and illustrated in the accompanying drawing in which:

Figure 1 is a perspective view of an embodiment of the invention, and

Figure 2 is a vertical, longitudinal sectional view thereof.

Referring more in detail to the drawing, the reference numeral 10 designates the drill which is constructed in accordance with the invention.

The bit comprises the tubular shank 12 which is internally threaded with left-hand round threads 14.

The shank is provided with the inclined oppositely positioned downwardly inclined ribs 16 having concave sides 18 and the upwardly tapered cutting edges 20.

The ribs 16 have flat upper surfaces 22, and these surfaces are provided with upwardly inclined reverse cutting blades 24 having the knife edge 26 extending from a point adjacent the cutting edges 20 to a point above the ribs 16 where the blades terminate in the cutting edges 28 having the knife edge 30 and these edges are in reverse relation to the edges 20.

The edges 20 are provided at their central point with the water inlets 32, and these inlets form a center point 34 which is at the center vertical line of the bit. These openings communicate with the water passage 36 as do the

openings 38 positioned in the shank 12 intermediate of the ribs 16, and the passage 36 communicates with the threaded bore of the shank.

It will be apparent from the foregoing description that a bit as above described will, with the use of the cutting blades 24 and edges 28, cut any rock falling on top of the bit, to permit easy removal of the bit as directed, thus preventing jamming of the bit and saving time in 10 its removal.

It is believed that the construction and advantages of the invention will be apparent to those skilled in the art, and it is to be understood that changes in the minor details of construction, arrangement and combination of parts may be resorted to, provided they fall within the spirit of the invention and the scope of the appended claim.

Having thus described the invention, what is 20 claimed as new and desired to be secured by Letters Patent is:

In a bit of the character described having an internally threaded tubular shank, the improvement comprising ribs on said shank in diametrically opposed relation to each other, said ribs having downwardly and outwardly inclined outer faces and concave sides, upwardly and outwardly tapered cutting edges on the outer lower ends of said ribs, upwardly and inwardly inclined cutting blades on the outer faces of said ribs centrally thereof, cutting edges on the upper ends of said cutting blades, a water inlet at the central vertical axis of the bit, a water passage in said shank centrally thereof forming a communication between said tubular shank and said water inlet and secondary water inlets in said shank intermediate of said ribs and communicating with said water passage.
